BUFFING MECHANISM FOR RAILWAY
CAR-END PLATFORMS

Leonard A. Marquardt, Elmhurst, Ill., assignor to
W. H. Miner, Inc., Chicago, Ill., a corporation
of Delaware

Application June 28, 1945, Serial No. 602,050

6 Claims. (Cl. 213—222)

1

This invention relates to improvements in buffing mechanisms for railway cars.

One object of the invention is to provide a buffing mechanism including the usual end platform and buffing face plate, supported by side stems, wherein the side stems are readily replaceable without disturbing the assembled condition of the mechanism.

Another object of the invention is to provide a buffing mechanism of the character indicated, wherein the parts are so designed that the side stems may be readily removed for repair or replacement without removal or detachment of the buffer face plate of the buffing mechanism.

A more specific object of the invention is to provide a buffing mechanism including the usual end platform, buffer face plate, and spring resisted side stems for supporting the buffer face plate from the platform, wherein the face plate is so designed and the buffer stems are connected thereto in such a manner that the latter may be readily assembled with and removed from the face plate by passing the same lengthwise through a suitable opening provided for that purpose in the vertical wall of the face plate.

Other objects of the invention will more clearly appear from the description and claims herein-after following.

In the drawings forming a part of this specification, Figure 1 is a fragmentary top plan view of a buffing device for railway cars embodying my invention. Figure 2 is a front elevational view of Figure 1, looking from left to right in said figure. Figure 3 is a front elevational view, on an enlarged scale, similar to Figure 2, showing the parts at one side of the mechanism. Figure 4 is a transverse, vertical sectional view, corresponding substantially to the line 4—4 of Figure 6, certain parts being omitted, and showing a step in the removal of the buffer stem. Figure 5 is a longitudinal, vertical sectional view, corresponding substantially to the line 5—5 of Figure 3. Figure 6 is a horizontal sectional view, corresponding substantially to the line 6—6 of Figure 4, the buffer side stem being shown in plan. Figure 7 is a transverse, vertical sectional view, corresponding substantially to the line 7—7 of Figure 5. Figure 8 is a detailed perspective view of the yoke-like locking element forming a part of the mechanism shown in Figures 1, 2, 3, 5, and 7.

Referring to the drawings, my improvement is shown in connection with a well-known type of buffing mechanism including the usual end platform 10 of a passenger car, having a central

2

pocket 11 in which the shock absorbing mechanism 12 is contained, and a central buffer stem 13 engaging the friction shock absorbing mechanism. The end platform is provided with the usual opening 14 through which the central buffer stem extends and in which it is guided. At opposite sides of the central buffer stem, the platform 10 is provided with the usual lengthwise extending openings 15—15 through which the buffer side stems extend, and rear supporting brackets 16—16 for guiding the buffer side stems.

In carrying out my invention, I provide broadly a buffer face plate A supported by a pair of spring opposed side stems B—B, and a pair of yoke-like members or clips C—C seated over the front ends of the stems B—B, the buffer face plate being provided with openings D—D therethrough, through which the buffer side stems may be passed, and which openings are blocked by the yoke-like clips C—C to prevent accidental turning and removal of the side stems.

The buffer face plate A, which is supported forwardly of the platform 10 by the side stems B—B, comprises a vertical front wall 17, top and bottom, rearwardly projecting, horizontal flanges 18 and 19, and vertical webs 20—20 and 20—20 extending between said top and bottom flanges and formed integral with said flanges and the front wall 17, thus providing rectangular pockets 21 at opposite sides of the face plate, which are adapted to accommodate the front ends of the side stems. At each pocket 21, the vertical wall 17 of the buffer face plate A is provided with a rectangular opening D which extends therethrough, the opening D being of greater length horizontally than vertically and of such a size as to permit the corresponding buffer side stem to pass therethrough in lengthwise direction when turned about its longitudinal central axis through an angle of 90 degrees from its normal assembled position. The horizontal length of the opening D preferably corresponds to the width of the pocket 21 into which it opens. Above and below the opening D, the inner side of the wall 17 of the face plate A presents vertical abutment faces 22—22 which are within the pocket D.

The buffer side stems B—B, which are disposed at opposite sides of the platform 10, are of like design. Each stem B comprises a cylindrical, rodlike rear end section or shank 23 and an enlarged front end section 24 of oblong, transverse cross section. A shoulder 124 is thus provided between the front end section 24 and the shank section 23. The section 24 has its opposite sides flattened and its top and bottom sides rounded

off, as most clearly shown in Figures 4 and 7. At the extreme forward end thereof, the section 24 of the stem is provided with a forwardly projecting, centrally disposed lug 25 of square cross section, the same being of such a size as to fit between the top and bottom walls of the opening D in the vertical front wall 17 of the buffer face plate A. The front end of the lug 25 is flush with the front face of the vertical wall 17 of the buffer face plate A.

The yokelike members C—C are of similar design, each being in the form of a U-shaped clip having a platelike flat bottom wall 26 and upstanding, laterally spaced side walls or arms 27—27. The arms 27—27 are provided with aligned openings 28—28 adapted to receive a headed locking pin 29. Each yoke C is attached to the front end portion of the corresponding side stem B and has the arms 27—27 thereof embracing opposite sides of the stem. The platelike bottom wall 26 of each clip C underlies the front end portion of the buffer side stem. The pins 29 serve to secure the side stems B—B to the buffer face plate A and the yokes C—C to the side stems. The pin 29 associated with each side stem extends through aligned openings 30—30 in the webs or side walls 20—20 of the corresponding pocket 21, an opening 31 in the buffer side stem B, and the openings 28—28 of the yoke C.

As will be seen upon reference to Figures 3 and 7, the arms 27—27 of the yokes or clips C—C are of such a height that they extend above and below the opening D of the buffer face plate A. Each yoke or clip C has the front ends of the walls 26 and 27—27 thereof abutting the vertical wall 17 of the face plate A, and inasmuch as each clip is rigidly secured to the corresponding buffer side stem by the pin 29, the clip or yoke serves as a reinforcing member, which, in effect, forms a head of said buffer stem bearing on the buffer face plate. Each clip or yoke C provides an effective locking means for holding the associated buffer side stem against turning about its longitudinal axis, thereby maintaining the same in the position shown in Figures 5 and 7 and in abutting relation with the front wall 17 of the buffer face plate.

Each buffer side stem B is provided with the usual spring 32 which surrounds the stem and bears at its front and rear ends respectively on the shoulder 124 of the stem and the corresponding bracket 16 of the end platform 10. Each stem B also has the usual retaining nuts 33 and 34 at the rear end thereof which abut the corresponding bracket 16 and limit forward movement of the stem B and the attached buffer face plate A.

To remove the buffer side stem B, the pin 29 is disengaged from the stem and yoke C. The yoke is then pushed or slid rearwardly on the stem and out of the pocket 21 and removed from the stem. The buffer stem is thus made free for turning about its longitudinal axis, and after removal of the retaining nuts 33 and 34, the stem may be turned through an angle of 90 degrees to register the vertically flattened front end portion thereof with the opening D of the buffer face plate A so that the stem may be withdrawn in forward direction through said opening.

In applying the buffer side stems, the procedure is substantially the reverse of that followed in removing the same.

I claim:

1. In a buffing mechanism for a railway car including an end platform, the combination with

4
a buffer face plate having a vertical front wall provided with an opening therethrough, said opening being of greater width than height; of a buffer side stem supporting said face plate from said end platform, said stem having the front end portion of elongated vertical cross section, and extending vertically across said opening and bearing on the inner side of said front wall above and below said opening, said front end portion of the stem being of a size to pass freely through said opening when the stem is turned about its longitudinal axis to an extent to register said front end portion with said opening; and a removable locking member having shouldered engagement with the face plate to hold said member against rotation about the axis of said stem, said member having arms embracing opposite vertical sides of said front end portion of the stem to hold the latter against rotation about its longitudinal axis with said stem positioned to abut said vertical wall above and below the opening thereof.

2. In a buffing mechanism for a railway car including an end platform, the combination with
25 a buffer face plate having a vertical front wall provided with an opening therethrough, said opening being of greater width than height; of a buffer side stem supporting said face plate from said end platform, said stem having the front end portion of elongated vertical cross section, and extending vertically across said opening and bearing on the inner side of said front wall above and below said opening, said front end portion of the stem being of a size to pass freely through said opening when the stem is turned about its longitudinal axis to an extent to register said front end portion with said opening; and a detachable U-shaped locking element having upstanding side arms embracing said stem at opposite vertical sides to hold said element and stem against relative rotation about the longitudinal axis of the stem, said locking element extending vertically across said opening of the vertical wall of the face plate and abutting the inner side of said wall above and below said opening, said element and buffer face plate having shouldered engagement with each other to hold said element against rotation with respect to the face plate.

3. In a buffing mechanism for a railway car including an end platform, the combination with
50 a buffer face plate having a vertical front wall provided with a rearwardly facing pocket of angular cross section, said wall of the plate having an opening therethrough at said pocket, said opening being of greater width than height; of a buffer side stem supporting said face plate from said end platform, said stem having a front end portion of elongated vertical cross section disposed within said pocket abutting the inner side of said vertical wall of the face plate above and below the opening thereof, said front end portion of the stem being of a size to pass freely through said opening when said buffer side stem is turned about its axis to an extent to register said front end portion with said opening; and a removable locking element within said pocket having shouldered engagement with the walls of said pocket to hold said element against rotation, said element embracing the vertical sides of said stem to lock the stem against rotation about its longitudinal axis.

4. In a buffing mechanism for a railway car including an end platform, the combination with
75 a buffer face plate having a vertical front wall provided with a rearwardly facing pocket of an-

gular cross section, said pocket being defined by vertical side walls and horizontal top and bottom walls, said wall of the plate having an opening therethrough at said pocket, said opening being of greater width than height; of a buffer side stem supporting said face plate from said end platform, said stem having a front end portion of rectangular cross section and of greater vertical height than width, said rectangular front end portion of the stem being disposed within said pocket and abutting the inner side of said vertical wall of the face plate above and below the opening thereof, said front end portion of the stem being of a size to pass freely through said opening when said buffer side stem is turned about its axis to an extent to register said front end portion with said opening; and a removable U-shaped locking element having upstanding side arms and a transverse bottom plate, said locking element being seated in said pocket with the arms thereof interposed between the sides of said front end portion of the stem and the side walls of said pocket, and the bottom plate interposed between the bottom wall of said pocket and the underneath side of said stem to lock said stem against rotation with respect to the face plate about the longitudinal axis of said stem.

5. In a device of the character described, the combination with a horizontally disposed plate having a vertical front wall provided with an opening therethrough, said opening being of greater width than height; of an elongated supporting bar for said plate, said bar having the front end portion of elongated vertical cross section, and extending vertically across said opening and bearing on the inner side of said front wall above and below said opening, said front end portion of the bar being of a size to pass freely through said opening when said bar is turned about its longitudinal axis to an extent to register said front end portion with said opening; and a detachable U-shaped locking element open at the top and having upstanding side arms embracing said bar at opposite vertical sides to hold said element and bar against relative rotation about the longitudinal axis of the bar, said locking element extending vertically across said opening of the vertical wall of the plate and abutting the inner side of said wall above and below said open-

ing, said element and plate having shouldered engagement with each other to hold said element against rotation with respect to said plate.

6. In a device of the character described, the combination with a member having a vertical wall provided with a projecting pocket portion of angular, interior cross section at one side thereof, said wall having an opening therethrough communicating with the inner end of said pocket, said opening being of greater width than height; of an elongated bar for supporting said member, the end portion of said bar at one end thereof being of elongated transverse vertical cross section, said end being disposed within said pocket in overhanging relation to said wall of said member above and below the opening thereof, said end portion of the bar being of a size to pass freely through said opening when said bar is turned about its axis to an extent to register said end with said opening; and a removable locking element within said pocket having shouldered engagement with the walls of said pocket to hold said element against rotation, said element embracing the vertical sides of said end of the bar to lock the bar against rotation about its longitudinal axis.
